UNITED STATES PATENT OFFICE.

MARCUS H. LIEN, OF KENNEBEC, SOUTH DAKOTA.

MILK-PAIL SUPPORT.

1,165,188.

Specification of Letters Patent. Patented Dec. 21, 1915.

Application filed June 8, 1915. Serial No. 32,903.

To all whom it may concern:

Be it known that I, MARCUS H. LIEN, a citizen of the United States, residing at Kennebec, in the county of Lyman and State 5 of South Dakota, have invented a new and useful Milk-Pail Support, and I do hereby declare the following to be a full, clear, and exact description of the invention, such as will enable others skilled in the art to which 10 it appertains to make and use the same.

This invention relates to an improved milk pail support, and an object of the invention is to provide a support of this design constructed of a single piece of sheet 15 metal, bent to detachably engage the peripheral bead of the pail, adjacent the bail ear of the pail, and curves to engage the leg slightly above the knee, to support the pail while milking, it being understood there are 20 to be two of such supports, one upon each side of the pail.

In practical fields the details of construction may necessitate alterations, falling within the scope of what is claimed.

25 The invention comprises further features and combination of parts, as hereinafter set forth, shown in the drawings and claimed.

In the drawings: Figure 1 is a view in side elevation of a milk pail, illustrating 30 two supports as applied to two diametrically opposite sides of the pail. Fig. 2 is an enlarged detail perspective view of one of the supports, illustrating the manner of its connection to the annular bead of the 35 pail. Fig. 3 is a vertical sectional view on line 3—3 of Fig. 2. Fig. 4 is an enlarged detail perspective view of the support detached. Fig. 5 is a sectional view on line 40 5—5 of Fig. 2, showing the bail handle detached.

Referring more especially to the drawings, 1 designates the milk pail, to be any suitable or convenient shape, and provided with an annular bead 2 at its upper edge. 45 Each support is constructed from a single piece of sheet metal, and comprises a plate 3, which is somewhat broad and has a curved tapering end 4. The other end (which is broad) has a pair of tongues 5, which are 50 curved downwardly partially, and under the bead 2 and bent upon themselves as at 6, and formed into rolls 7, portions of which

conform at 8, to the downward and under curvature of the tongues. The rolls 7, as shown, engage the bead 2 of the pail, and 55 the tongues, beyond the rolls as shown at 9 extend downwardly and engage on the inner periphery of the pail, and being that there are two supports of similar construction, a milk pail may be firmly supported 60 between the legs just beyond the knees while milking. The adjacent edges of the portions (which extend down and under the outer portion of the bead 2) of the tongues 5 are provided with lugs 10 extending toward each other, between which lugs and the edge 11 of the support the bail ear 12 passes. It is to be observed that the weight 65 of the pail and the contents therein tends to cause the support to bend upwardly and 70 toward the ear 12. But this action is very materially prevented owing to the edge 11 engaging the ear 12, which also prevents the downwardly and under extending parts 75 of the tongues 5, from disengaging the bead of the pail. If the bent portion 6 does not engage the outer periphery of the pail adjacent the under part of the bead, but which will occur in some instances, the lugs 10 will prevent downward movement of the supports, and will also insure firmness or 80 rigidity. In applying each of the supports, the same is passed downwardly so that the ear 12 will pass between said lugs 10 and the edge 11, and the parts 9 are sprung so as 85 to admit of the bead 2 into the rolls 7. A milk pail equipped with supports of this construction is ready for use, the supports acting to hold the pail, without the same 90 being clenched between the legs. 90

The invention having been set forth, what is claimed as new and useful is:

A milk pail support comprising an elongated sheet metal plate curved to conform to the curvature of the leg, said plate having 95 a pair of tongues spaced apart from each other and extending from one end thereof, said tongues for a portion of their length being bent down and under the bead of a milk pail, and bent upon themselves, and then 100 formed into rolls and having their extremities beyond the rolls engaging upon the inner periphery of the pail, the bead engaging said rolls, portions of which conform to the

downward and under curved portion of said tongues, the space between the tongues adjacent the end edge having the tongue receiving the bail ear of the pail, the adjacent edges of the rolls of said tongue having lugs extending toward each other, between which lugs and the end edge of the plate having the tongues said bail ear engages.

In testimony whereof I have signed my name to this specification in the presence of two subscribing witnesses.

MARCUS H. LIEN.
